UNITED STATES PATENT OFFICE.

EDWARD M. HAYMAKER, OF CENTERVIEW, MISSOURI.

MILK-PAIL COVER AND STRAINER.

SPECIFICATION forming part of Letters Patent No. 739,080, dated September 15, 1903.

Application filed April 14, 1903. Serial No. 152,490. (No model.)

To all whom it may concern:

Be it known that I, EDWARD M. HAYMAKER, a citizen of the United States, residing in Centerview, county of Johnson, State of Missouri, have invented certain new and useful Improvements in Milk-Pail Covers and Strainers, of which the following is a specification.

My invention relates particularly to covers for milk-pails; and my main object is to provide an improved mechanism for straining the milk before admitting the same to the pail.

The invention is fully described in connection with the accompanying drawings, and the novel features are particularly pointed out in the claims.

Figure 1 is a sectional elevation of my improved straining-cover applied to a milk-pail. Fig. 2 is a partial plan view of the same. Fig. 3 is a separate view of the inner clasp-20 ring, and Fig. 4 is a reduced plan view of the flat filtering-cover.

A represents the top portion of a milk-pail, upon the beaded edge 1 of which the downwardly-flanged rim 2 of the pail-cover 3, with its beaded edge 4, is snugly fitted, three crimps or depressions 5 in said edge 4 being preferably provided, as indicated in Fig. 2, to facilitate the operations of attaching and detaching the cover. The main portion of this cover 3 is preferably formed, as shown, from a circular disk of sheet metal having a central opening. The rim 6 of the latter is downwardly and outwardly flanged, as indicated, to serve as a filter-clasping nozzle-rim, as hereinafter explained, and the sloping portion adjacent to said nozzle forms a somewhat flattened funnel or funnel-bottom 7, extending to the circular ridge 8, beyond which latter is the reverse slope 9, joining the previously-described downwardly-flanged and beaded rim 2, as shown in Fig. 1. The body 10 of the funnel is separately formed and suitably connected to the main cover 3 at or adjacent to the ridge 8.

In connection with the cover 3 I employ a separately-formed settling-receptacle 11, made from a single piece of sheet metal pressed to shape, as shown, to form a shallow vessel of considerably larger diameter than the funnel-nozzle 6, having its central bottom portion 12 elevated to receive the milk deliv-

ered from the funnel-nozzle, and a depressed annular settling chamber or gutter 13. The rim 14 of this settling-receptacle rises above the raised bottom 12, so as to provide for retaining a proper depth of liquid therein to insure the settling of heavy foreign matter into the annular chamber 13, and it is so shaped as to serve, in connection with the outer clasp-ring 15 on the cover hereinafter referred to, the purpose of clamping the circular outer edge of the filtering-cover 16, as indicated. This filtering-cover for the settling-receptacle, which is provided for the purpose of straining the milk as it overflows from the receptacle into the pail, is a separately-formed and readily-renewable covering in the form of a flexible disk with a central opening and is preferably made of fibrous material, as cotton-battin, held between two layers of cheese-cloth and having an outer diameter somewhat greater than the diameter of the receptacle-rim 14 and a central opening somewhat smaller than the funnel-nozzle 6, so as to provide overlapping inner and outer edges 17 and 18 for clamping the same respectively between the outer clasp-ring 15 and the rim 14 of the receptacle and an inner clasp-ring 19 and the nozzle-rim 6. The ring 15 is removably held in concentric position upon the under surface of the cover by a circular series of guide-lugs 20, fixed to the latter, thus permitting of its being easily removed and cleaned. The inner ring 19, as shown in detail in Fig. 3, is a split one formed of spring-wire to permit of its being readily sprung upon or removed from the nozzle-rim 6 to clasp or release the inner edge 18 of the filtering-cover. The abutting ends 23 of the wire are rounded, as shown in Fig. 3, to facilitate cleaning. The outer edge 17 of the filtering-cover is pressed against the ring 15 by the conically-formed rim 14 of the settling-receptacle when the latter is secured to the cover. The means provided to effect this connection to the cover preferably consist of a central standard 21, rigidly fixed to the cover and provided, as shown, with a hooked head 26, and an engaging arm or bar 22 therefor, fixed to the cover above the nozzle-rim 6 in proper shape and position to readily engage the standard for the purpose of secur-

ing the receptacle, while at the same time permitting its convenient disconnection when desired.

To provide for reducing the mouth of the funnel-body 10 when desired, I employ a removable cover-ring 24, which is sprung upon the beaded edge 25 in the same manner as the cover 3 is sprung upon the edge of the pail.

In assembling the parts of the complete cover as above described they are built upon in reverse position, the settling-receptacle being put in place after the outer clasp-ring 15 is in position and after the filtering-cover has been clamped at its inner edge to the nozzle- 15 rim by means of the ring 19. The head of the standard 21 will engage the bar 22 in any position, firmly clamping the outer edge of the filtering-cover. When applied to the pail and in service, the milk falling through the funnel-nozzle upon the raised central portion 11 of the settling-receptacle is quietly distributed throughout the latter. As it accumulates therein any heavy particles contained in it settle into the annular chamber 13, and 25 the only outlet being through the filtering-cover 17 all foreign matter is effectively removed from the milk as it filters through the latter and overflows the rim 14 of the receptacle 11 into the pail. A new filtering-cover 30 may be employed whenever desired, and every part of the device may be readily cleaned with the greatest possible ease and thoroughness.

The essential features and advantages of my improved construction have been made 35 apparent in connection with the foregoing description, and it will be readily understood that the specific construction set forth may be considerably modified without departing from the spirit of my invention.

40 What I claim is—

1. In a milk-pail strainer the combination with a cover having a central opening or nozzle and a concentric receptacle removably secured below said opening, of a separately-formed filtering-disk of flexible material having a central opening smaller than said nozzle, the inner circular edge of said disk being clamped to the nozzle and its outer circular edge clamped to the rim of said receptacle to 45 form a removable annular covering for the latter beyond said nozzle.

2. A milk-pail strainer comprising a cover having a funnel-shaped central portion with a filter-clasping nozzle-rim and a suitably-attached outer clasp-ring concentric with said nozzle-rim and a concentric settling-receptacle detachably secured to said cover below said opening and having a rim adapted to cooperate with said outer clasp-ring.

60 3. A milk-pail strainer comprising a cover having a funnel-shaped central portion with a filter-clasping nozzle-rim and a suitably-attached outer clasp-ring concentric with said nozzle-rim, a concentric settling-receptacle detachably secured to said cover below said opening and an annular filtering-cover for said receptacle having its inner edge clamped

to said nozzle-rim and its outer edge between the rim of the receptacle and said outer clasp-ring.

70 4. A milk-pail strainer comprising a cover having a funnel-shaped central portion with a filter-clasping nozzle-rim and a suitably-attached outer clasp-ring concentric with said nozzle-rim, a settling-receptacle below said nozzle having a rim corresponding in size with said outer clasp-ring, and an attaching means for said receptacle comprising a central post fixed thereto and an engaging bar therefor in the cover.

75 5. The combination with the pail-cover having a funnel-shaped central portion, of the settling-receptacle below said cover of greater diameter than the funnel-nozzle, and having its central bottom portion elevated and a depressed annular settling-chamber.

80 6. In a milk-pail strainer the combination with a cover having a central opening or nozzle and a concentric receptacle removably secured below said opening, of a separately-formed filtering-disk comprising two layers of fabric covering an interposed layer of filtering material and having a central opening smaller than said nozzle, the inner circular edge of said disk being clamped to the nozzle 90 and its outer circular edge clamped to the rim of said receptacle to form a removable annular covering for the latter beyond said nozzle.

95 7. In a milk-pail strainer the combination with a cover having a central opening or nozzle with an outwardly-turned edge, and concentric receptacle removably secured below said opening, of a separately-formed filtering-disk having a central opening, a clasp-ring 100 for removably securing the circular inner edge of said disk to said nozzle and means for clamping the circular outer edge of the same to the concentric rim of said receptacle.

105 8. A milk-pail strainer comprising a cover 105 formed with a funnel-shaped central portion having a discharge-nozzle, and a reversely-sloped outer portion, a separately-formed filtering-disk of flexible material with a central opening having its circular inner edge removably clamped to said nozzle, a concentric receptacle below said nozzle having a rim portion adapted to engage the circular outer edge of said disk against the reversely-sloped portion of the cover, and means for attaching said receptacle to the cover substantially as set forth.

115 9. The combination with a milk-pail cover having a funnel-shaped central portion with a flanged nozzle-rim, of the split clasp-ring 120 therefor having its abutting edges beveled substantially as and for the purpose set forth.

125 In testimony whereof I affix my signature in the presence of two witnesses.

EDWARD M. HAYMAKER.
